UNITED STATES PATENT OFFICE.

ISAIAK HELLER, OF BROOKLYN, NEW YORK.

WAISTBAND BUTTONHOLE STRIP.

Application filed June 29, 1922. Serial No. 571,743.

To all whom it may concern:

Be it known that I, ISAIAK HELLER, a citizen of the United States, residing at Brooklyn, in the county of Kings and State 5 of New York, have invented a certain new and useful Improvement in Waistband Buttonhole Strips, of which the following is a specification, reference being had therein to the accompanying drawing.

10 This invention relates to an improved waist-band button hole strip for use in connection with boys' trousers and shirt-waists and one object of the invention is to provide a button hole strip which is so constructed that the button holes will not be liable to tear.

Another object of the invention is to so construct this button hole strip that it may have a double thickness through which the 20 button holes will be formed, one thickness being formed of material which is relatively stiff and the second thickness being formed of material which is soft.

Another object of the invention is to so 25 construct this button hole strip that the pieces of material from which it is formed may be very firmly connected at the upper or outer edge of the strip.

This invention is illustrated in the accompanying drawing, wherein:

Figure 1 is a view looking at one side of the button hole strip.

Figure 2 is a view looking at the opposite side of the button hole strip.

35 Figure 3 is a sectional view taken along the line 3—3 of Fig. 1.

This button hole strip is provided with a main strip 1 which will be formed of some stiff fabric such as drilling or the like. The second or auxiliary strip 2 is formed of some soft fabric such as sateen or the like and this intermediate strip is placed against inner face of the main strip 1. A backing strip 6 is placed against the intermediate strip with its edge portion extending slightly beyond the edge of the main strip and intermediate strip. The extended edge portion of the intermediate or soft strip 2 is turned over the edge of the main strip 1 and 45 stitches passed through the folded edge portion 50

tion and through all of the strips to form a seam 3 which serves to securely hold the strips in engagement with each other. After the strips have been secured, the button holes 4 are formed through the strips as 55 shown in Fig. 3 and the usual button hole stitching provided as shown at 5. It should be noted that the button holes extend from the seam 3 to a point in spaced relation to the free edge of the strips 2 and 6. 60 Therefore, when these button holes are formed and finished by the button hole stitching as shown at 5, a button hole strip will be provided in which the button holes will be formed through more than a single 65 layer of fabric and therefore the button holes will not be liable to readily tear. It should be further noted that by having the strip 1 formed of stiff drilling, the strip 2 formed of soft material such as sateen, and 70 the strips 6 of an intermediate grade the liability of tearing is reduced, this being due to the fact that the strip 2 is soft and gives the desired toughness and prevents tearing of the other strips. 75

I claim:

1. A button hole strip comprising outer strips and an intermediate strip between said outer strips, one of said outer strips being extended above the upper edges of the 80 second outer strip and intermediate strip and folded down upon the outer face of the second outer strip and secured by stitching passing through all of said strips, one of said strips being formed of fabric softer 85 than one of the remaining strips but not as soft as the other of the said remaining strips, said strips having button holes formed therethrough and extending from a point adjacent the joined upper edge portions thereof to a point in spaced relation to the lower edge of the intermediate strip. 90

2. A button hole strip comprising a main strip formed of stiff fabric, an intermediate strip formed of soft fabric and extending 95 along the upper portion of said main strip, and a backing strip formed of fabric stiffer than the intermediate strip but not as stiff as the main strip, the backing strip being placed against the intermediate strip and 100

2
having its upper edge portion extending beyond the upper edge thereof and folded down upon the outer face of the main strip, and securing stitches passed through the fold and upper edge portions of said strips to secure the same, said strips having button-holes formed therethrough and extend-

ing from a point adjacent the joined upper edge portions of the strips to a point in spaced relation to the lower edges of the intermediate and backing strips. 10

In testimony whereof I hereunto affix my signature.

ISAAK HELLER.
